SPINNING APPARATUS

Robert H. Roughsedge, Ramsey, N. J., and Hans G. Lustig, New York, N. Y., assignors to Celanese Corporation of America, a corporation of Delaware

Application July 13, 1948, Serial No. 38,516

20 Claims. (Cl. 18—8)

1

This invention relates to spinning apparatus, and relates more particularly to novel spinning apparatus including means for protecting and wiping a spinning jet.

In the production of filaments by the so-called dry-spinning process, a solution of filament-forming material in a volatile solvent is pumped or otherwise forced through a spinning jet located in a spinning cabinet or metier. As the filaments pass through the metier, the solvent is removed from said filaments by means of a suitable evaporative medium, and the filaments are then drawn from the metier to any suitable filament take-up apparatus. If the flow of filament-forming solution through the spinning jet is interrupted, by failure of power to the spinning pumps or for any other reason, the fine orifices in the spinning jet are likely to become clogged since the evaporative medium in the metier will cause the evaporation of the solvent from whatever filament-forming solution remains in the jet. This clogging usually makes it necessary to dismantle and clean the spinning jet before spinning can be resumed.

It is an important object of this invention to provide a novel and simple apparatus which will protect the spinning jet and prevent clogging of the jet orifices when the flow of filament-forming material is interrupted.

A further object of this invention is to provide a simple apparatus which will seal the spinning jet from the medium inside the metier and supply a flow of liquid over the jet, when the flow of filament-forming material is interrupted.

Still another object of this invention is to provide a simple apparatus which will wipe the spinning jet thereby removing any solid materials which may have accumulated on the surface thereof.

Other objects of this invention, together with certain details of construction and combinations of parts, will appear from the following detailed description and claims.

One preferred embodiment of our invention is illustrated in the accompanying drawings in which

Figure 1 is an elevational view, partly in section, of the jet protector applied to a metier including two spinning jets,

Figure 2 is a bottom view, looking upwardly and partly in section of the jet protector,

Figure 3 is a plan view of the jet protector,

Figure 4 is a fragmentary cross-sectional view of the actuating mechanism for the jet protector taken on the line 4—4 of Figure 2 and

2

Figure 5 is a circuit diagram of the control system for the jet protector.

Referring now to the drawings for a detailed description of this invention, there is shown a spinning cabinet or metier, generally indicated by reference numeral 1, containing two spinning units 2. Each of the spinning units 2 includes a spinning jet 3 provided with any desired number of fine orifices through which filament-forming material is forced into a setting medium to form filaments. In accordance with this invention, protectors are provided for each of the jets 3. Since the jet protectors are substantially identical in construction, only one will be described in detail in the interest of brevity.

The jet protector mechanism is mounted on wall 4 of the metier 1 on a level with the spinning jet 3 and includes suitably aligned bearing members 7 and 8 supported in a framework 9. The bearing members slidably support actuating shaft 11 extending through an opening 12 in the wall 4 and through a hole 13 in connecting block 14, to which the shaft is adjustably fastened by means of set screw 16. Encircling the actuating shaft 11 is a helical spring 17, which is held compressed between the connecting block 14 and a washer 18 bearing against the framework 9. The other end of the connecting block 14 is adjustably fastened, as by means of set screw 19, to shaft 21 of an air cylinder, generally indicated by reference numeral 22. By introducing a supply of compressed gas into the air cylinder 22 through hose connection 23, the shaft 21, the connecting block 14 and the actuating shaft 11 will be forced against the helical spring 17 to assume the position indicated by the dotted lines in Figures 2 and 4 of the drawings, and thereby actuate the jet protector as will be set forth below. Release of pressure from the air cylinder 22 will permit the helical spring 17 to expand, returning the actuating shaft 11, the connecting block 14 and the shaft 21 to their original position.

The actuating shaft 11 carries a yoke 24 having a shaft 26 mounted between its arms, which shaft 26 passes through an elongated slot 28 in a crank arm 29. The crank arm 29, lever arm 31, collar 32 and shaft 33 rotate as a unit and are mounted for free rotation and lateral motion in bearing plates 34 and 36, fastened to the wall 4. The shaft 33 and the assembly it supports may be positioned vertically by means of adjusting screw 37 and lock-nut 38 carried by the bearing plate 36.

Mounted at the free end of the lever arm 31

is a cup 39 having its edge 41 at an angle to its longitudinal axis for engagement with the edge 43 of the complementary cup 42 carried by the spinning unit 2. The two cups 39 and 42 together with gasket 44 mounted in the edge 43 will effectively seal the spinning jet 3 from the medium inside the metier 4, when the cups are aligned and the adjusting screw 37 is positioned to bring the edge 41 into contact with the gasket 44.

The cup 39 is provided with a centrally located aperture 45 through which wiper indexing shaft 46 passes and a liquid-tight seal is effected between the cup 39 and the wiper indexing shaft 46 by means of gasket 41, held in position by liquid distributing plate 48. A pin 49 extending from the wiper indexing shaft 46 engages one of four apertures 51 in wiper plate 52, which plate carries sponge-rubber wipers 53 in a generally U-shaped channel 54. The wiper plate 52 also includes a depending split shaft 56 for frictional engagement with hole 57 in the upper end of wiper indexing shaft 46. In Figure 3 of the drawings, wiper plate 52 is omitted from the right-hand jet protector, to illustrate more clearly the structure of the liquid distributing plate 48. A passageway 59, having a hose coupling 61 and opening into the channel 63 in the liquid distributing plate 48 is provided to permit a liquid to be introduced into the cup 39. From the channel 63 the liquid may pass through apertures 64 in the liquid distributing plate 48, apertures 66 in the wiper plate 52, over the spinning jet 3 and over the sponge-rubber wipers 53 to passageways 67 in the outer circumference of the liquid plate 48. From the passageways 67 the liquid may then pass into circumferential channel 68, between the liquid distributing plate 48 and the cup 39, and from the channel 68 to passageway 69 provided with hose coupling 72. Flexible hoses 73 and 74 are fastened to the couplings 61 and 72 to permit the liquid to be brought to and led from the cup 39.

The wiper indexing shaft 46 has fastened thereto as by means of set screw 76, ratchet wheel 77, provided with ratchet teeth 78. A shield 80 surrounds and protects the ratchet wheel 77 and is provided with a centrally located aperture through which a bolt 79, whose function will be set forth in detail below, passes for threaded engagement with the indexing shaft 46. In Figure 2 of the drawings the shield 80 is omitted from the right-hand jet protector to illustrate more clearly the ratchet construction. The ratchet wheel 77 is driven by means of a U-shaped driving member, generally indicated by the reference numeral 81, having the end portions of both its upper arm 82 and its lower arm 83 enlarged and provided with apertures 84 and 86 respectively. The upper arm 82 passes through opening 87 in the shield 80 and has the aperture 84, positioned for free rotation about wiper indexing shaft 46. The lower arm 83 passes below the shield 80 and has the aperture 86 positioned for free rotation about the bolt 79. A flat spiral spring 88, having one end fastened to the cup 39 and the other end fastened, by means of pin 89, to the ratchet driving member 81, is tensioned to urge the ratchet driving member 81, of the jet protector shown in the right half of Figures 1 and 2 of the drawings, in a clockwise direction. The rotation of the ratchet driving member 81 is limited by stop 91, which is adjustably fastened to the bearing plate 36 by means of set screw 92. The ratchet driving member 81 carries an operating pawl 93, having a

catch 94 formed in one end thereof, and mounted on the cup 39 are the cooperating lock pawl 96 which engages the ratchet teeth 78 and spring catch 97 positioned to engage the catch 94 of the operating pawl 93. A bar 98, fastened to spacer 99 on the cup 42 carries bolt 101 held in position by lock nut 102, and positioned to pass through aperture 103 in the shield 80 and strike the spring catch 97.

During operation, as the actuating shaft 11 operated by the air cylinder 22 carries the lever arm 31 and the cup 39 to the position shown by the dotted lines in Figure 2 of the drawings, the ratchet driving member 81 is rotated counterclockwise, torsioning the spring 88 and causing the spring catch 97 to engage the catch 94, thereby locking the ratchet driving member 81 in place. The rotation of the ratchet driving member also carries the operating pawl 93 counterclockwise to the next ratchet tooth 78, the ratchet being held from counterclockwise rotation by means of the lock pawl 96. When the lever arm 31 returns the cup 39 to its sealing position with the cup 42, the ratchet driving member 81 is held stationary until the spring catch 97 is released by striking the end of the bolt 101. Thereupon the torsion in the spring 88 rotates the ratchet driving member 81 clockwise, carrying with it the ratchet pawl 93 and the ratchet wheel 77, indexing the wiper plate 52 and thereby rotating the sponge-rubber wiper 53 until it presents a fresh surface for contact with the face of the spinning jet 3.

A control circuit for the jet protector is shown in Figure 5 of the drawings as connected between spinning pump motor 106 and motor starter 107. Starting of the spinning pump motor 106 applies a voltage between terminals 108 and 109, so that closing of the normally open push-button switch 111 permits a current to flow through holding coil 112 and through solenoid coil 113. After the push-button switch 111 is released current continues to flow to the solenoid coil 113 through switch 114, which is held closed by the holding coil 112. The solenoid coil 113 draws valve operating arm 116 to the left rotating air-valve 117 and liquid valve 118 to the spinning position shown in solid lines. In the spinning position the air valve 117 permits a flow of compressed air from any suitable source (not shown) through air lines 119 and 121 to the air cylinder 22. Conversely, when the liquid valve 118 is in the spinning position it will prevent the flow of liquid from supply tank 122 through liquid line 123 to the cup 39. In the event that power to the spinning pump motor 106 is cut off, the flow of current through the solenoid coil 113 will cease and the valve operating arm 116 will move the air valve 117 and liquid valve 118 to the protecting position shown in dotted lines. When the air valve 117 is in the protecting position it will shut off the flow of air through air line 119 and will permit the air cylinder 22 to exhaust the air it contains to the atmosphere. In contrast, when the liquid valve 118 is in the protecting position it will permit a flow of liquid from the supply tank 122 through the liquid line 123 to the cup 39. The liquid head in the supply tank 122 necessary to insure an adequate liquid flow may be readily obtained by positioning the tank 122 above the cup 39 or by applying a suitable gas pressure to the free space above the liquid. A normally closed push-button switch 124 in the line from 70 the terminal 108 permits the flow of current

through the solenoid coil 113 to be interrupted independently of the spinning pump motor 106 if desired. As an alternative the control circuit may be connected to a pressure operated switch in the supply line for the filament-forming solution, as well as to the power supply line as shown. Any number of jet protectors may be controlled by means of a single circuit, and the greatest flexibility of operation will be attained when a separate control circuit is provided for each spinning jet or for all the spinning jets in a single metier.

When spinning is to be initiated the spinning pump motor 106 is started by means of motor starter 107 and when the motor 106 is delivering full pressure upon the spinning jet 3, the push-button switch 111 is closed permitting a current to flow through the solenoid coil 113 rotating the air valve 117 and liquid valve 118 to the spinning position. This will cut off the flow of liquid from the supply tank 122 to the cup 39 and will apply air pressure to the air cylinder 22 moving the actuating shaft 11 against the compression of the helical spring 17 thereby rotating the crank arm 29 and the lever arm 31 to the position shown in dotted lines in Figure 2 of the drawing. The lever arm 31 will carry the cup 39 from engagement with the cup 42 providing a free path for passage of filament-forming material from the spinning jet 3 through the metier 1. The rotation of the lever arm 31 will also rotate the ratchet driving member 81 torsioning the spring 88 and engaging the spring catch 97 with the catch 94. Upon failure of power to the spinning pump motor 106, the flow of current through the solenoid coil 113 will cease and the air valve 117 and the liquid valve 118 will be operated to their protecting positions by means of the valve operating arm 116. Thereupon the air in the air cylinder 22 will be exhausted into the atmosphere permitting the helical spring 17 to expand, carrying with it the actuating shaft 11 which will rotate the crank arm 29 and the lever arm 31 to the position shown in full lines in Figure 2 of the drawings thereby bringing the cup 39 into alignment with the cup 42 and sealing the spinning jet 3 from the medium inside the metier 1. As the lever arm 31 brings the cup 39 into engagement with the cup 42 the bolt 101 will strike the spring catch 97 releasing the catch 94, permitting the torsion in the spring 88 to index the sponge-rubber wiper 53. Simultaneously with the release of air pressure from the air cylinder 22 a flow of liquid from the supply tank 122 will be established, by means of the liquid valve 118, to the cup 39, over the spinning jet 3 and over the sponge-rubber wiper 53. The protecting cups 39 and 42, plus the flow of liquid over the spinning jet 3 will prevent the evaporation of solvent from any residual filament-forming solution in the jet, thereby avoiding the clogging of the jet orifices. When spinning is resumed, the motion of the lever arm 31 as it moves the cup 39 from its protecting position will pass the wet sponge-rubber wiper 53 over the spinning jet 3 removing any solid materials from the surface of the jet. After four cycles of operation the sponge-rubber wiper 53 must be replaced which may be readily accomplished by lifting the entire wiper plate 52 and substituting another plate in its stead.

The jet protector may also be employed to wipe the surface of the spinning jet 3 without interrupting the power to spinning pump motor 106 by opening the normally closed push-button

switch 124. This will interrupt the flow of current to the solenoid coil 113 and initiate the protecting cycle to remove any solid material which may have formed on the surface or in the orifices of the spinning jet 3 as the result of a filament break or in any other manner.

The choice of a liquid for passage over the spinning jet 3 is not critical so long as it removes the filament-forming material from the surface of the jet. Acetone will function satisfactorily when the filament-forming solution includes a cellulose ester such as cellulose acetate, but other cellulose acetate solvents may be employed. After passage through the cup 39 the acetone may be purified in any manner desired and returned to the supply tank 122.

The jet protector of this invention is useful not only in the so-called dry-spinning process, but also in other spinning processes wherein a jet is employed. For example, it may be employed to protect a spinning jet in the melt-spinning process, wherein a melt of filament-forming material is forced through a spinning jet into a cooling atmosphere, or in the wet-spinning process wherein a solution of filament-forming material is forced through a spinning jet into a precipitation or coagulation bath.

Any suitable materials may be employed for the construction of the jet protector illustrated, and the layout and structure of the jet protector may be varied to adapt it to the metier construction. Other actuating means such as a solenoid may be substituted for the air actuating means shown, although the air actuating means is especially effective and inexpensive.

It is to be understood that the foregoing detailed description is given merely by way of illustration and that many variations may be made therein without departing from the spirit of our invention.

Having described our invention, what we desire to secure by Letters Patent is:

1. In a filament spinning apparatus wherein a filament-forming material is passed through a hardening medium, a spinning jet having at least one spinning orifice and having one surface exposed to the hardening medium, pressure means for forcing a filament-forming material through said spinning jet and into the hardening medium, and means relatively movable with respect to the spinning jet for sealing the exposed surface of said spinning jet from the hardening medium in said spinning apparatus, said latter means being carried by said spinning apparatus and normally out of contact with the exposed surface of said spinning jet.

2. In a filament spinning apparatus wherein a filament-forming material is passed through a hardening medium, a spinning jet having at least one spinning orifice, pressure means for forcing a filament-forming material through said spinning jet, means relatively movable with respect to said spinning jet for sealing said spinning jet from the medium in said spinning apparatus, and means for supplying a flow of liquid over said spinning jet when said spinning jet is sealed from the medium in said spinning apparatus.

3. In a filament spinning apparatus wherein a filament-forming material is passed through a hardening medium, a spinning jet having at least one spinning orifice, pressure means for forcing a filament-forming material through said spinning jet, means relatively movable with respect to said spinning jet for sealing said spinning jet from the medium in said spinning apparatus,

means for supplying a flow of liquid over said spinning jet when said spinning jet is sealed from the medium in said spinning apparatus, a wiping material and means for passing the wiping material over said spinning jet to remove any material from the surface of said spinning jet.

4. In a filament spinning apparatus wherein a filament-forming material is passed through a hardening medium, a spinning jet having at least one spinning orifice and having one surface exposed to the hardening medium, pressure means for forcing a filament-forming material through said spinning jet and into the hardening medium, and means automatically operative upon failure of said pressure means and relatively movable with respect to the spinning jet for sealing the exposed surface of said spinning jet from the hardening medium in said spinning apparatus, said latter means being carried by said spinning apparatus and normally out of contact with the exposed surface of said spinning jet.

5. In a filament spinning apparatus wherein a filament-forming material is passed through a hardening medium, including a spinning jet having at least one spinning orifice and pressure means for forcing a filament-forming material through said spinning jet, the improvement which comprises means in said spinning apparatus operative upon failure of said pressure means, and relatively movable with respect to said spinning jet, for sealing said spinning jet from the medium in said spinning apparatus, and means for supplying a flow of liquid over said spinning jet when said spinning jet is sealed from the medium in said spinning apparatus.

6. In a filament spinning apparatus wherein a filament-forming material is passed through a hardening medium, including a spinning jet having at least one spinning orifice and pressure means for forcing a filament-forming material through said spinning jet, the improvement which comprises means in said spinning apparatus, operative upon failure of said pressure means, and relatively movable with respect to said spinning jet, for sealing said spinning jet from the medium in said spinning apparatus, and means operable upon restoration of pressure in said pressure means for moving said sealing means with respect to said spinning jet to expose said spinning jet to the medium in said spinning apparatus.

7. In a filament spinning apparatus wherein a filament-forming material is passed through a hardening medium, including a spinning jet having at least one spinning orifice and pressure means for forcing a filament-forming material through said spinning jet, the improvement which comprises means in said spinning apparatus, operative upon failure of said pressure means, and relatively movable with respect to said spinning jet, for sealing said spinning jet from the medium in said spinning apparatus, means operable upon restoration of pressure in said pressure means for moving said sealing means with respect to said spinning jet to expose said spinning jet to the medium in said spinning apparatus and means for supplying a flow of liquid over said spinning jet when said spinning jet is sealed from the medium in said spinning apparatus.

8. In a filament spinning apparatus wherein a filament-forming material is passed through a hardening medium, including a spinning jet having at least one spinning orifice and pressure means for forcing a filament-forming material through said spinning jet, the improvement which comprises means in said spinning appa-

ratus, operative upon failure of said pressure means, and relatively movable with respect to said spinning jet, for sealing said spinning jet from the medium in said spinning apparatus, a wiping material and means operable upon restoration of pressure in said pressure means for passing the wiping material over said spinning jet and for moving said sealing means with respect to said spinning jet to expose said spinning jet to the medium in said spinning apparatus.

9. In a filament spinning apparatus wherein a filament-forming material is passed through a hardening medium, including a spinning jet having at least one spinning orifice and pressure means for forcing a filament-forming material through said spinning jet, the improvement which comprises means in said spinning apparatus, operative upon failure of said pressure means, and relatively movable with respect to said spinning jet, for sealing said spinning jet from the medium in said spinning apparatus, means for supplying a flow of liquid over said spinning jet when said spinning jet is sealed from the medium in said spinning apparatus, a wiping material and means operable upon restoration of pressure in said pressure means to pass the wiping material over said spinning jet and for moving said sealing means with respect to said spinning jet to expose said spinning jet to the medium in said spinning apparatus.

10. In a filament spinning apparatus wherein a filament-forming material is passed through a hardening medium, a spinning jet having at least one spinning orifice and having one surface exposed to the hardening medium, pressure means for forcing a filament-forming material through said spinning jet, a wiping material, and means in said spinning apparatus, normally out of contact with said spinning jet, relatively movable with respect to said spinning jet for passing the wiping material over the exposed surface of said spinning jet.

11. In a filament spinning apparatus wherein a filament-forming material is passed through a hardening medium, a spinning jet having at least one spinning orifice and having one surface exposed to the hardening medium, pressure means for forcing a filament-forming material through said spinning jet, a wiping material, means for supplying a flow of liquid over said spinning jet and means in said spinning apparatus relatively movable with respect to said spinning jet for passing the wiping material over the exposed surface of said spinning jet.

12. In a filament spinning apparatus wherein a filament-forming material is passed through a hardening medium, including a spinning jet having at least one spinning orifice and pressure means for forcing a filament-forming material through said spinning jet, the improvement which comprises a wiping material, means in said spinning apparatus relatively movable with respect to said spinning jet for passing the wiping material over said spinning jet and means for moving said wiping material to present a fresh surface to said spinning jet after each pass thereof over said spinning jet.

13. In a filament spinning apparatus wherein a filament-forming material is passed through a hardening medium, including a spinning jet having at least one spinning orifice and pressure means for forcing a filament-forming material through said spinning jet, the improvement which comprises means surrounding said spinning jet and having an opening through which

said filament-forming material may pass and means, normally out of contact with said spinning jet, relatively movable with respect to said spinning jet for closing said opening, whereby said spinning jet is sealed from the medium in said spinning apparatus.

14. In a filament spinning apparatus wherein a filament-forming material is passed through a hardening medium, including a spinning jet having at least one spinning orifice and pressure means for forcing a filament-forming material through said spinning jet, the improvement which comprises means surrounding said spinning jet and having an opening through which said filament-forming material may pass, means relatively movable with respect to said spinning jet for closing said opening, whereby said spinning jet is sealed from the medium in said spinning apparatus and means for supplying a flow of liquid over said spinning jet when said spinning jet is sealed from the medium in said spinning apparatus.

15. In a filament spinning apparatus wherein a filament-forming material is passed through a hardening medium, including a spinning jet having at least one spinning orifice and pressure means for forcing a filament-forming material through said spinning jet, the improvement which comprises means surrounding said spinning jet and having an opening through which said filament-forming material may pass, means, normally out of contact with said spinning jet, for closing said opening, whereby said spinning jet is sealed from the medium in said spinning apparatus, and wiping means carried by said closing means for wiping the surface of said spinning jet.

16. In a filament spinning apparatus wherein a filament-forming material is passed through a hardening medium, including a spinning jet having at least one spinning orifice and pressure means for forcing a filament-forming material through said spinning jet, the improvement which comprises means surrounding said spinning jet and having an opening through which said filament-forming material may pass, cup-shaped means for closing said opening whereby said spinning jet is sealed from the medium in said spinning apparatus, and means for supplying a flow of liquid to said cup-shaped means and over said spinning jet when said spinning jet is sealed from the medium in said spinning apparatus.

17. In a filament spinning apparatus wherein a filament-forming material is passed through a hardening medium, including a spinning jet having at least one spinning orifice and pressure means for forcing a filament-forming material through said spinning jet, the improvement which comprises means surrounding said spinning jet and having an opening through which said filament-forming material may pass, cup-shaped means, normally out of contact with said spinning jet, for closing said opening whereby said spinning jet is sealed from the medium in said spinning apparatus, and wiping means carried by said cup-shaped means for wiping the surface of said spinning jet.

18. In a filament spinning apparatus wherein a filament-forming material is passed through a hardening medium, including a spinning jet having at least one spinning orifice and pressure means for forcing a filament-forming material through said spinning jet, the improvement which comprises means surrounding said spin-

ning jet and having an opening through which said filament-forming material may pass, cup-shaped means for closing said opening whereby said spinning jet is sealed from the medium in said spinning apparatus, wiping means carried by said cup-shaped means for wiping the surface of said spinning jet, and means for moving said wiping means to present a fresh surface to said spinning jet after each pass thereof over said spinning jet.

19. In a filament spinning apparatus wherein a filament-forming material is passed through a hardening medium, including a spinning jet having at least one spinning orifice and pressure means for forcing a filament-forming material through said spinning jet, the improvement which comprises means surrounding said spinning jet and having an opening through which said filament-forming material may pass, cup-shaped means for closing said opening whereby said spinning jet is sealed from the medium in said spinning apparatus, wiping means carried by said cup-shaped means for wiping the surface of said spinning jet, means for moving said wiping means to present a fresh surface to said spinning jet after each pass thereof over said spinning jet, and means for supplying a flow of liquid to said cup-shaped means and over said spinning jet and said wiping means when said spinning jet is sealed from the medium in said spinning apparatus.

20. In a filament spinning apparatus wherein a filament-forming material is passed through a hardening medium, including a spinning jet having at least one spinning orifice and pressure means for forcing a filament-forming material through said spinning jet, the improvement which comprises annular means surrounding said spinning jet and having an opening through which said filament-forming material may pass, cup-shaped means mounted on a lever arm for motion to close said opening and seal said spinning jet from the medium in said spinning apparatus, actuating means operative upon failure of said pressure means to move said lever arm and cup-shaped means to sealing position, means operable upon restoration of said pressure means to move said lever arm and cup-shaped means out of sealing position, wiper means carried by said cup-shaped means for wiping said spinning jet as said lever arm and cup-shaped means are moved out of sealing position, ratchet means actuated by the motion of said lever arm and cup-shaped means for moving said wiper means to present a fresh surface to said spinning jet after each pass thereof over said spinning jet, and means for supplying a flow of liquid to said cup-shaped means and over said spinning jet and said wiper means when said spinning jet is sealed from the medium in said spinning apparatus.
